UNITED STATES PATENT OFFICE.

EDWARD F. SMITH, OF ROCHESTER, NEW YORK, ASSIGNOR TO JOSIAH ANSTICE, OF ROCHESTER, NEW YORK.

LOCK FOR PAPER-TOWEL HOLDERS AND THE LIKE.

1,206,609.

Specification of Letters Patent. Patented Nov. 28, 1916.

Application filed January 19, 1916. Serial No. 73,037.

To all whom it may concern:

Be it known that I, EDWARD F. SMITH, a citizen of the United States, residing at Rochester, in the county of Monroe and State of New York, have invented certain new and useful Improvements in Locks for Paper-Towel Holders and the like, of which the following is a specification, reference being had therein to the accompanying drawing.

My invention relates to improvements in locks for paper towel holders and the like.

The object of my invention is to provide a lock for roll holders of this character in which the roll is locked in the holder until it is entirely used up and thus prevent the stealing of the paper from the holder.

Another object of my invention is to provide a simple, cheap and effective lock of this character which can be readily applied to any of the well-known roll holders, and having certain details of structure and operation hereinafter more fully described.

In the accompanying drawing Figure 1 is a front view of a roll holder showing the roll in section and showing my lock applied. Fig. 2 is an enlarged perspective view showing the two parts of my lock in their separate relation. Fig. 3 is a vertical sectional view of the locking means carried by one of the plates.

Referring now to the drawing, 1 represents an ordinary holder for towels and the like and which comprises a spring wire 1, having the loops 2, formed as shown, and the wire of said loop extending downwardly at 3 and 4, forming the vertically disposed arms, as clearly shown at Fig. 1 of the drawing. The lower ends of the wires of the arms 3 and 4 are coiled forming the two cone-shaped members 5 and 6, which are adapted to enter the core 7 of the roll of paper 8, and allowing the paper to freely rotate thereon. By this structure, it will be seen that the cores 5 and 6 frictionally engage the core 7 of the roll 8, and hold it against a free rotation. I have shown this form of holder for a practical application of my invention, but it is understood that the same can be readily applied to any well-known form of holders.

Fitting within the cone 5 is a head 9, which is preferably cone-shaped and of cast metal and having on its inner face a central hollow depressed portion 10 provided with

an ear 11 in which is rigidly secured the rod 12. This rod, as shown in the drawings, is eccentrically arranged and of a length to extend entirely through the core 7 of the roll 8. While I have shown this rod 12 eccentrically arranged for the purpose of application to this specific form of roll holder, yet it will be understood that the said rod can be concentrically arranged within the head 9, without departing from my invention. This rod 12 could be loosely connected to the head 9, or it could have a shoulder on the end thereof, which would drop into a socket in the head and could not be removed until the roll was used up and the core removed. Fitting within the cone-shaped member 6 is a head 13, which like the head 9, is preferably cone-shaped and has in its inner face a central cut-away portion 14. Said central cut-away portion is provided with an eccentrically arranged opening extending entirely through the outer face of the head.

Carried by the upper edge of the head 13, by the rivet 16 is a spring member 17, which extends downwardly and intersects the opening 15, passing through the head 13. This spring, as shown in Fig. 3 of the drawing is set at a slight angle, so the rod is free to move to the right, but cannot be moved to the left without forcing the spring inwardly within the cut-away of the head 13. The rod 12 passes into the opening 15 and the spring moves inwardly freely and allows of the free passage of the said rod through the opening to the right. When the rod has reached its limit of movement through the opening any backward pull upon the rod causes the spring 17 to bite into the rod and hold the head against outward movement. By this arrangement it will be seen that the roll holder is held so that the arm cannot be moved outwardly and the rod 12 locks the two arms of the holder against outward movement and absolutely prevents the roll of paper from being removed from the holder. In order to move the heads 9 and 13 outwardly, it is necessary to press the spring inwardly within the recess 13 and can only be accomplished after the roll of paper is entirely used up and the core 7 cut away so that the spring can be thus operated.

As heretofore stated, while I have shown and described this specific form of heads

9 and 13, it will be understood that they could be made perfectly flat and which would enable the invention to be applied to any of the well-known roll holders in which two arms are employed to support the roll of paper. It will also be understood that both heads 9 and 13 can be constructed exactly alike so that they both move on the rod independent of each other.

10 Having thus described my invention, what I claim and desire to secure by Letters Patent is:

1. The combination with a paper roll holder, comprising two laterally movable arms having at their ends means for supporting a roll, of a locking device carried at one end, means for engaging the free end of one of said arms and a member movable on the other end of the rod outside of the arm and carrying a locking member engaging the said rod.

2. A locking device for roll holders, having roll supporting arms and transverse openings, the locking device comprising a rod passing through the said openings and having at one end a member engaging one arm and a member longitudinally movable on the other end of the rod, said member carrying a lock at its inner side whereby the lock is inaccessible while the roll is in position in the holder.

3. A locking device for roll holders having roll supporting arms provided with transverse openings, the locking device comprising a rod having one end operatively engaging one of the arms, the other end of the rod passing through the opening of the other arm, a member slideable upon the rod and carrying a locking device at its inner side for locking it on the rod, one of said arms movable inward when the paper roll is used up to permit ready access to the locking member to release it from the rod for the placing of an unused paper roll in position on the holder arms.

4. The combination with a paper roll hav-

ing roll supporting arms, one of which is laterally movable, of a separate locking device therefor, the locking device comprising a rod adapted to pass through the ends of the arms, one end of the rod constructed to operatively engage one of the arms, the other end of the rod passing through the other arm and projecting therebeyond, and a member slideable upon the projecting end of the rod to engage the outside of the arm, said member carrying a spring lock at its inner side to lock against the rod, whereby the lock is inaccessible when the paper roll is in position.

5. A lock of the character described, comprising a head, a rod eccentrically carried by the inner face of the head, a second head having a thickened portion at one side and provided with a recess, a head having an opening therethrough communicating with the recess, a leaf-spring rigidly carried by the head and arranged at an angle thereto and having a flat outer edge intersecting the opening in the second head whereby the said head is free to move inwardly on the rod to hold it against movement thereon.

6. A lock of the character described comprising a head, a rod rigidly carried by the inner face of the head, a second head having a thickened portion provided with a recess communicating with an opening through the same, said head having a thickened portion opposite the first mentioned thickened portion, a leaf spring rigidly carried by said second thickened portion arranged at an angle to the head and intersecting the recess carried by the other thickened portion, whereby the edge of the leaf-spring engages the rod and locks the head thereon against outward movement.

In testimony whereof I hereunto affix my signature in the presence of two witnesses.

EDWARD F. SMITH.
